UNITED STATES PATENT OFFICE.

JOSEPH C. O'NEILL AND JOHN S. DYE, OF TRENTON, NEW JERSEY.

AUTOMATIC SAFETY CHECK-VALVE.

975,153.

Specification of Letters Patent.

Patented Nov. 8, 1910.

Application filed May 11, 1910. Serial No. 560,612.

To all whom it may concern:

Be it known that we, JOSEPH C. O'NEILL and JOHN S. DYE, citizens of the United States, residing at Trenton, in the county 5 of Mercer and State of New Jersey, have invented a certain new and useful Improvement in Automatic Safety Check-Valves, of which the following is a specification.

Our invention relates to a new and useful 10 improvement in safety check valves, and has for its object to provide an exceedingly simple and effective device of this character, which will eliminate the danger of boiler explosions, caused by the water becoming low 15 or at a dangerous level.

The objects of the invention are obtained by constructing a check valve which will prevent water entering the boiler after the water in said boiler has reached a dangerous 20 level or has been entirely exhausted.

Another object of the invention is to provide a check valve of the character described with means for preventing back pressure from the boiler.

25 With these ends in view, this invention consists in the details of construction and combination of elements hereinafter set forth and then specifically designated by the claims.

30 In order that those skilled in the art to which this invention appertains may understand how to make and use the same, we will describe its construction in detail, referring by letter to the accompanying drawing 35 forming a part of this specification, in which—

Figure 1 is a vertical sectional view of a safety check valve made in accordance with our improvement, and Fig. 2, a section at 40 the line $x-x$ of Fig. 1.

In carrying out our invention as here embodied, A represents a casing, having an inlet B from the water supply, and outlet C to the boiler and an opening D whereby 45 the interior of the casing may be reached without uncoupling the water system.

With the interior of the casing is formed an integral spout E by the lid F dependently mounted upon the arm G, said arm 50 being swingingly mounted upon the bolt H which passes through the walls of the casing, having a nut I mounted thereon to hold it in place.

J is a guide having a flange K formed 55 with its upper end, said flange adapted to

rest upon the outer end of the walls, forming the opening D when said guide has been inserted in said opening D. This guide has an aperture L formed in one side thereof and this aperture is placed opposite the lid 60 F to allow for the free movements of said lid.

At the lower end of the guide J is formed a seat M for the reception of the float valve N. The guide J fits snugly within the opening D and its lower end rests against an extension or partition O whereby the water passing through the casing from the water supply to the boiler must pass through the 70 opening L and downward through the guide J.

P denotes a cap threaded upon the casing over the opening D, thereby holding the guide J in place and preventing the passage 75 of water through the opening D.

The operation of the device is as follows:—The cap P is removed and the water allowed to flow to the boiler, the float valve N is then placed in the guide which will cause it to flow in said guide in proximity to its upper end, and the force of the water holding the lid F upward, a portion thereof will extend into the guide, so that the float valve N cannot reach the seat M. Should the water for any reason cease to flow to the 80 boiler, the lid F will close by gravity and prevent back pressure. As the water is used from the boiler the float valve N will gradually descend until it takes its seat M, and when in this position should the water be turned on it will enter the guide above the valve, and the pressure of said water will hold said float valve upon its seat, preventing its passage to the boiler. The lid F at this time will be above the float valve N and will further prevent the rise of the float. After the boiler has been cooled down, the cap P may be removed and the float valve N again placed in the water after it has been 90 again turned on.

From this description it will be seen that a check valve constructed in accordance with our improvement will prevent the flow of water to the boiler after the water in said boiler has reached a dangerous level, in this way overcoming the possibility of explosions.

Of course we do not wish to be limited to the exact details of construction here shown, as these may be varied within the limits of 110

the appended claims without departing from the spirit of our invention.

Having thus fully described our invention, what we claim as new and useful, is—

5 1. In a check valve, a casing having an inlet, an outlet and an opening, an internal spout formed integral with the walls of the casing relatively near the inlet, a guide provided with an aperture and valve seat mounted in the opening, a float valve placed in said guide, a lid, and a swinging arm on the free end of which is mounted said lid, said lid adapted to close the spout for preventing back pressure and for holding the 10 float valve up or down, depending upon the position of said float valve.

2. In a check valve, a casing having an inlet, an outlet and an opening, an internal spout formed integral with the walls of the casing relatively near the inlet, a guide provided with an aperture and valve seat mounted in the opening, a float valve placed in said guide, a bolt passing through the walls of the casing, an arm swingingly mounted 20 thereon, a lid mounted upon the free end of said arm for closing the spout for holding the float valve up or down, depending upon the position of said float valve, and a cap threaded over the opening to hold the guide 25

in place and prevent the passage of water through said opening.

3. In a check valve, a casing having a passageway therethrough, a guide having an inlet and an outlet at right angles to one another, said guide being mounted in the 35 casing and extending into the passageway, and a float valve placed in said guide, said valve being at one time above and at another time below the line of the liquid flow.

4. In a check valve, a casing having an 40 inlet and an outlet, a guide having a valve seat and an aperture at right angles to one another mounted in the casing, a float valve contained in said guide, said valve being at one time above and at another time below 45 the aperture, and means for preventing the passage of the valve from one position to the other while the liquid remains under pressure in the casing.

In testimony whereof, we have hereunto 50 affixed our signatures in the presence of two subscribing witnesses.
